(57) **CLAIM**

The ornamental design for a container for pre-moistened field towels, as shown and described.

DESCRIPTION

FIG. 1 is a perspective view of a container for pre-moistened field towels showing my new design;

FIG. 2 is a side elevational view thereof;

FIG. 3 is a top plan view thereof; and,

FIG. 4 is a bottom plan view thereof.

The broken-line disclosure in the views is understood to represent unclaimed subject matter which forms no part of the claimed design.
